UNITED STATES PATENT OFFICE.

EDGAR D. HOSTLER, OF TIPTON, IOWA, ASSIGNOR OF ONE-HALF TO HAMIEL & MATHER,
OF TIPTON, IOWA, A PARTNERSHIP.

VULCANIZER.

1,338,569.

Specification of Letters Patent. Patented Apr. 27, 1920.

Application filed July 30, 1919. Serial No. 314,220.

To all whom it may concern:

Be it known that I, EDGAR D. HOSTLER, a citizen of the United States, and a resident of Tipton, in the county of Cedar and State 5 of Iowa, have invented a new and Improved Vulcanizer, of which the following is a full, clear, and exact description.

This invention relates to improvements in vulcanizers, and more particularly to an im- 10 proved mandrel for use in vulcanizing the ends of the inner tubes for tires and the like, an object of the invention being to provide a device of the character stated which permits the tube ends to be vulcanized 15 on the outside thereof, thus permitting a ready manipulation of the tube so as to insure a proper positioning of the parts and also permit a full observation of the vul- canizing process.

20 A further object of the invention is to provide a mandrel having a plurality of vul- canizing surfaces of different diameters and shapes so as to accommodate various sizes of tube and permit various kinds of vul- canizing processes to be carried out.

25 A further object is to provide a mandrel having a steam chamber therein which effectually heats the outer surface of the mandrel and which is insulated by means 30 of an asbestos or other non-heat conducting lining from the inner surface of the man- drel, and provide an entrance slot or recess into the interior of the mandrel for the 35 positioning of a tube end therein and locate in said entrance slot a removable filler piece which conforms in shape to the inner and outer surfaces of the mandrel.

With these and other objects in view the 40 invention consists in certain novel features of construction, and combinations and ar- rangements of parts, as will be more fully hereinafter described and pointed out in the claims.

In the accompanying drawings—

45 Figure 1 is a view in side elevation illustrating one form of my invention;

Fig. 2 is an end view thereof;

Fig. 3 is a view in longitudinal section showing a slightly modified shape of outer 50 surfaces for the mandrel;

Fig. 4 is a view in transverse section on the line 4—4 of Fig. 3;

Fig. 5 is a view in longitudinal section of the mandrel shown in Fig. 1, illustrating the method of vulcanizing thereon;

Figs. 6 and 7 are views in longitudinal section illustrating modifications; and

Figs. 8, 9, 10, 11, 12, 13 and 14 are views illustrating other modifications.

Referring particularly to Figs. 1, 2, 3, 4, 5, 6 and 7, 1 represents the mandrel which is preferably integral with a base 2 and is provided with a longitudinal cylindrical bore 3 having a lining 4 of asbestos or other non-heat conducting material therein. The 65 body 1 is made with a steam chamber 5 which is supplied with the steam by means of circulating pipes 6 communicating with the base 2.

In Figs. 1, 2 and 5 the body 1 is formed 70 exteriorly with a plurality of vulcanizing surfaces 7 of different diameters and of different inclination so that any surface desired may be utilized for vulcanizing.

In Fig. 3 the outside face of the body is 75 of general tapering or conical form which permits the vulcanizing process to be carried out at any point on the conical surface in accordance with the diameter of the tube being vulcanized. An additional vulcanizing surface is provided by means of an ex- 80 tension 8 on one end of the body and this extension may be integral with the body or may constitute a separate part, as indicated by reference numeral 13 in Figs. 6 and 7. 85 Where the extension is a separate piece, it is understood it will fit snugly within the bore of the body and may be made tapering as indicated, and if desired, an annular shoulder 15, such as shown in Fig. 7, may 90 be employed to limit the inward movement of the extension and insure a tight juncture against the body. It is, of course, to be understood that the extensions will have similar asbestos or other non-heat conduct- 95 ing linings 14 and where the extensions are separate pieces, they are preferably of two halves held together when in place in the body.

The body 1 is made with a longitudinal en- 100

trance slot 9 through which the tube may be moved to position the same in the mandrel or to remove the tube therefrom. This slot 9 is normally closed by a filler piece 10 which may be secured in any approved manner. I have illustrated as a securing means, transversely positioned pins 11 projecting through the filler piece 10 and resting in small recesses 12 in the body.

10 In the modification illustrated in Figs. 8, 9, 10, 13 and 14, the mandrel 16 is of general cylindrical form having a filler piece 17 therein, the latter engaging the body portion of the mandrel by means of a longitudinal key 19 and groove 18 so that it can be slid readily from the body, and the pin 20 in the filler piece limits the longitudinal movement in one direction to hold the filler piece in normal position. This mandrel 16 is provided with a lining 4 and is made hollow forming a steam chamber 21 having steam pipes 22 communicating with the same at one end of the mandrel. To increase the diameter of the mandrel, a removable shell 23, shown in Figs. 11, 12 and 13, may be employed. This shell is made of two halves fitting the mandrel 16 and having longitudinal flanges 24 which take the place of the filler piece 17 and hold the shell on the mandrel. The inwardly projecting flange 25 at one end of the shell bears against the end of the mandrel and limits its movement in one direction.

35 The tubes to be vulcanized are indicated by the reference numerals 26 and 27. A strip of quick curing gum 28 is used to join the two ends together and binding strips 29 are used to hold the tube ends in vulcanizing position on the mandrel, as will now be explained.

In carrying out the method of vulcanizing on my improved mandrel, the following steps are preferably employed.

45 The surfaces of the tubes 26 and 27 to be united are first roughened slightly and then washed with gasoline, after which a coating of quick curing vulcanizing cement is applied to the roughened surfaces. This is allowed to set for the proper time, say five 50 minutes. A strip of quick curing gum indicated by the reference numeral 28 is then placed between the surfaces treated, as above, and allowed to set until the parts are connected. The tube is then inserted in 55 the mandrel by first removing the filler piece 10 and after the filler piece has been replaced, the tube 27 is reversed or turned inside-out so that it will assume the position shown in Figs. 5 and 14. The point 60 of vulcanizing is located on the proper surface of the mandrel to snugly fit the same, and the binding strip 29, preferably of rubber, is wrapped around the jointed ends of the tube to tightly hold the same against

the vulcanizing surface of the mandrel. 65 Steam is then admitted to the mandrel for the proper length of time to thoroughly vulcanize the parts together. When the vulcanizing operation is completed, the strip 29 is removed and the tube ends removed 70 from the mandrel.

Various slight changes may be made in the general form and arrangement of parts described without departing from the invention, and hence I do not limit myself to 75 the precise details set forth but consider myself at liberty to make such changes and alterations as fairly fall within the spirit and scope of the appended claims.

I claim:

1. A device of the character stated, comprising a hollow mandrel having an exterior vulcanizing surface, and a non-heat conducting lining in the interior of the mandrel.

2. A device of the character described, comprising a mandrel having a bore therethrough, a non-heat conducting lining in the bore, said mandrel having a steam chamber therein, and having an exterior vulcanizing surface.

3. A device of the character stated, comprising a hollow mandrel having an exterior vulcanizing surface, a non-heat conducting lining in the interior of the mandrel, said mandrel having a longitudinal 95 entrance slot communicating with the interior thereof, and a filler piece normally filling the slot.

4. A device of the character described, comprising a mandrel having a longitudinal bore and having a steam chamber therein, said mandrel having a longitudinal entrance slot, a filler piece normally closing the slot, said mandrel and filler piece having an inner non-heat conducting lining, and said mandrel having an exterior vulcanizing surface.

5. A device of the character described, comprising a mandrel having a longitudinal bore and having a steam chamber therein, said mandrel having a plurality of exterior vulcanizing surfaces of varying diameters and shapes.

6. A device of the character described, comprising a mandrel having a longitudinal bore and having a steam chamber therein, an extension projecting from the mandrel and having a bore therethrough, and a lining of non-heat conducting material in the bore of the mandrel and the extension.

7. A device of the character described, comprising a mandrel having a longitudinal bore and having a steam chamber therein, said mandrel having a longitudinal entrance slot, a filler piece normally closing the slot, a shell adapted to fit the mandrel and provide a larger vulcanizing surface thereon, said shell consisting of two halves,

and a longitudinal flange on each half adapted to enter the entrance slot to replace the filler piece of the mandrel.

8. A device of the character described, comprising a mandrel having a longitudinal bore and having a steam chamber therein, said mandrel having a longitudinal entrance slot, a filler piece normally closing the slot, a shell adapted to fit the mandrel and pro-

vide a larger vulcanizing surface thereon, 10 said shell consisting of two halves, a longitudinal flange on each half adapted to enter the entrance slot to replace the filler piece of the mandrel, and an internally projecting flange at one end of the shell engaging 15 the end of the mandrel.

EDGAR D. HOSTLER.
